US00D976219S

(12) **United States Design Patent** (10) Patent No.: **US D976,219 S**
(45) Date of Patent: **** Jan. 24, 2023**

(54) **LAMP BAND INTERFACE**

(71) Applicant: **Chengxun Cai**, Guangdong (CN)

(72) Inventor: **Chengxun Cai**, Guangdong (CN)

(73) Assignee: **Shenzhen Chuangpu Technology Co., Ltd**, Guangdong (CN)

(**) Term: **15 Years**

(21) Appl. No.: **29/702,450**

(22) Filed: **Aug. 20, 2019**

(51) LOC (14) Cl. **14-03**

(52) U.S. Cl.

USPC **D13/168**

CPC **H05B 45/20** (2020.01)

(58) **Field of Classification Search**

(57) **CLAIM**

The ornamental design for a lamp band interface, as shown and described.

DESCRIPTION

FIG. 1 is a perspective view of a lamp band interface showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
